CLAIM

The ornamental design for a lightbulb dimmer socket, as shown.

DESCRIPTION

FIG. 1 is a perspective view taken from the direction of the base of the light bulb dimmer socket showing my new design;

FIG. 2 is a perspective view taken from the direction of the socket thereof;

FIG. 3 is a side elevational view thereof;

FIG. 4 is a cross sectional view taken in line 4—4 of FIG. 3.

FIG. 5 and 6 are plan views thereof taken from the direction of the base and socket, respectively.
